UNITED STATES PATENT OFFICE.

JOHN BRADLEY, OF NORTH CHELMSFORD, MASSACHUSETTS.

STRIPING MECHANISM FOR KNITTING-MACHINES.

SPECIFICATION forming part of Letters Patent No. 448,007, dated March 10, 1891.

Application filed April 29, 1890. Serial No. 349,924. (No model.)

To all whom it may concern:

Be it known that I, JOHN BRADLEY, of North Chelmsford, in the county of Middlesex and State of Massachusetts, have invented certain new and useful Improvements in Striping Mechanism for Knitting-Machines, of which the following is a specification.

My invention relates to knitting-machines designed to knit plush-faced fabrics—that is, fabrics having a body knitted in any suitable way and a so-called “plush yarn” locked or knitted into the body fabric at suitable intervals, but yet so as to float on one surface of the body fabric and form a lofty face thereon. As fabrics of the kind mentioned are used the plush face becomes the right side. The plush thread or yarn is usually introduced by means of a “filling-wheel,” so called, which lays the yarn to form the plush or fleece behind certain needles and in front of others, which position permits of its being locked or looped with the body fabric formed from the yarn introduced by the ordinary loop or stitch wheel. The filling-wheel is arranged at an angle with respect to the needles contrary to that at which the stitch-wheel is arranged, and is consequently revolved in a contrary direction, carrying the yarn controlled by it down upon the needles, while the stitch-wheel carries its yarn upward on the stems of the needles.

It is frequently desirable that the plush or fleece face should be formed in varying colors or designs, and it is to meet this end that my present improvement has been contrived, which improvement consists in combining a striping mechanism—that is, a mechanism employing yarn-guides which may be thrown into and out of action in any predetermined order—with a filling-wheel.

The invention will first be described in connection with the accompanying drawings and the letters of reference marked thereon, forming a part of this specification, and then be pointed out in the claim appended to the general description.

In the said drawings, Figure 1 is a top view of a circular-knitting machine equipped with my improvement. Fig. 2 is a detail in perspective, showing a portion of the yarn-guides, the filling-wheel, and co-operative parts. Fig. 3 is a sectional view showing the manner in

which the yarn-guides may be actuated to bring them into and throw them out of operation.

The same letters of reference indicate the same parts in all the figures.

In the drawings, *a* designates a needle-cylinder, *b* the needles, *c* the ordinary yarn-guide, *d* the stitch-wheel, *e* the presser-wheel, and *f* the push-back, all of which may be of common construction, and which, with the landing and knocking-over wheels, may be employed to produce an ordinary knitted web.

g designates the “filling-wheel,” so called, which is plugged between its leaves or wings, as at *h*, in order that it may press back the needles at its plugged point and lay the yarn fed by the wheel in front of the needles so pressed back, while the nibs on the wings *i* will carry the yarn over and down behind the needles with which they co-operate.

Instead of feeding but a single yarn to the filling-wheel, as heretofore, I employ a striping mechanism to feed various colored yarns automatically at predetermined intervals to the filling-wheel, as hereinbefore stated. The said striping mechanism may be of any suitable form or organization. As herein shown, it consists of reciprocating yarn-guides *j*, controlled in their operation by a pattern-plate *k*, which is actuated by a lever *l*, carrying a pawl *m*, the said lever being moved by a cam *r* on the knitting-head *a*, as is common in such devices.

When in the rotation of pattern-plate *k* a pin *s* in the face thereof is brought under the heel *t* of a yarn-guide *j* the forward end of the guide will be lowered into action, and when the said pin passes from under the heel of the yarn-guide the spring *u*, connected at one end to a lug *v*, extending above the pivotal point of the yarn-guide and at the other end to a stationary part of the machine or frame, will operate to raise the forward end of the guide out of operative position, carrying the heel *t* down upon the plain face of the pattern-plate, as is clearly shown in Fig. 3.

When it is desired to bring a particular yarn into position to be fed to the needles by the filling-wheel, the end of the yarn-guide carrying such yarn is lowered, so as that the wings *i* of the filling-wheel may catch the yarn and introduce it to the needles, as before described, and

- when the yarn is to be changed the yarn-guide lowered into operative position will be raised, so that the stitch-wheel will not catch the thread being carried by it, and another yarn-guide will be lowered into position occupied by the first-named guide. When a yarn is thrown out of action by the raising of the forward end of a yarn-guide, such yarn will be caught between two wings *i* of the filling-wheel and be carried over and down upon the face of the wheel under a spring-finger *n* and between the fingers *o o* of a yarn holder and breaker *p*. The spring *n* is fixed upon and supported by the stud upon which the filling-wheel *g* turns.
- 15 The yarn holder and breaker *p* is arranged so as to extend in close proximity to the needles, so that the yarn will be brought into frictional contact with the needles at a point between the latter and the yarn-holder *p*, and so effect the breaking of the yarn at that point.
- 20 It is obvious that I may employ a filling-wheel of different construction from that

herein shown, as well as a striping mechanism of different form and arrangement, without departing from the nature or spirit of my invention.

Having thus explained the nature of my invention and described means whereby it may be used, I declare that what I claim is—

The combination, with a needle-cylinder and needles, of a filling-wheel adapted to lay a yarn behind certain needles and in front of others, a plurality of yarn-guides, and means for throwing said yard-guides into and out of action with relation to the filling-wheel and needles, as set forth

In testimony whereof I have signed my name to this specification, in the presence of two subscribing witnesses, this 26th day of April, A. D. 1890.

JOHN BRADLEY.
